UNITED STATES PATENT OFFICE

WILLIAM P. PRINGLE, OF WASHINGTON, DISTRICT OF COLUMBIA

SPARK PLUG TOOL

Application filed October 4, 1928. Serial No. 210,327.

This invention relates to a combined tool for use in connection with spark plugs of internal combustion engines, and aims to provide a cleaning element adapted to thoroughly remove all carbon deposits and other foreign matter from the inner surface of the shell and outer surface of the center porcelain, including the crevice at the junction between said shell and porcelain, and including the under surface of the shell flange. Other aims of the invention are to provide a gauge by which the air gap between the spark plug points may be readily measured, and a file for use in dressing said points.

15 Further objects and advantages of my invention will be apparent from the following specification and accompanying drawings, which represent a preferred illustrative embodiment thereof.

20 In the drawings, wherein like reference numerals refer to similar parts throughout,

Fig. 1 is an elevation of one side of my improved tool, also illustrating in partial section so much of a spark plug as is necessary 25 to show its application to the cleaning operation; and

Fig. 2 is an elevation of the opposite side of the tool.

My improved tool, which is preferably 30 made from an integral piece of steel about $3/64$ of an inch thick, consists of a cleaning element or head 1 connected by a neck 2 to a handle 3 of greater width, this handle being again reduced at the opposite end as at 4 and 35 terminating in a gauge disk 5. The handle may be provided with a file section, such as 6, on either side.

The head is of elongated triangular shape 40 having one edge 7, in the present embodiment, on or parallel to the center line of the tool.

The other edge 8 is inclined thereto at an angle, forming a long narrow sharp point 9. The neck 2 is somewhat narrower than the greatest width of the head 1, by reason of a 45 shoulder 10 formed by a short edge perpendicular to the edge 7 at the base of the head. The edges 11 and 12 of the neck 2 are parallel, the edge 11, in the form of the invention herein illustrated, being approximately equal in 50 length to the edge 7 and the edge 12 continu-

ing backward as at 13, forming one edge of the handle 3. An inclined edge 14, directed backward and outward, and joining an edge 15 parallel to the edge 13, brings the handle to its full width. 55

The head and neck and their various elements are so proportioned as to fit into a spark plug in the manner shown in Fig. 1, and it is to be understood that they may be so shaped and varied in their dimensions and 60 proportions as to operate upon any spark plug of unusual size or shape without departing from the spirit of my invention.

In operation, to clean a spark plug, the tool is turned sideways to admit the head between the porcelain 16 and the end flange 17 of a spark plug shell 18. The tool is then turned into a tangential or radial position, as shown in Fig. 1, bringing the shoulder 10 against the inner side of the flange 17 and 65 the edge 7 against the inside of the shell 18, after which the interior surfaces are scraped in obvious manner. To clean the carbon from the angle between the porcelain and the shell, the tool is moved inward, bringing 70 the point 9 into this angle or crevice, the length of the neck 2 being sufficient to allow such movement. The porcelain itself is scraped by the edge 8, which is shaped to conform to a porcelain of standard make. The 75 handle may be either smooth, as shown in Fig. 1, or may include an abrasive portion, such as file teeth or the like, as shown at 6 in Fig. 2. The use of the file and of the gauge portion 5 is so obvious as to require no further description. 80

It is to be understood that I do not limit myself to the exact form of my invention herein shown and described, but that what I claim is:

1. A spark plug cleaner comprising a head of general triangular outline, including a long narrow sharp point adapted to reach to the bottom of the spark plug air space, the opposite end of said head comprising a 95 shoulder adapted to engage the under surface of a plug shell flange, an edge between the point of said shoulder, and the point of said head adapted to scrape the inside of a shell, a neck having one side in a straight line 100

parallel to the side of said head adjacent said shoulder, said neck being of such width as to be operable between the inner rim of said flange and the center porcelain.

5 2. A spark plug cleaner consisting of a piece of material comprising a handle portion terminating at one end in a cleaning head, said cleaning head being connected to said handle by a neck of reduced width, said head tapering to a point, and having one straight and one scraping edge inclined with reference thereto, said straight edge being offset from said neck by a short perpendicular edge forming a shoulder, said shoulder being in line with the juncture of said inclined edge with said neck.

10 3. A combination spark plug tool comprising a piece of substantially flat material formed into a head, a neck, a handle joined to said head by said neck, the edges of said neck and of said handle and one edge of said head lying in parallel lines, the other edge of said head diverging from said first edge at an acute angle, thereby forming an elongated point, and joining one edge of said neck at the rear of said head, another edge at the rear of said head directed perpendicularly to the first mentioned edges of said neck, forming a shoulder.

15 3. In testimony whereof, I have signed my name to this specification.

WILLIAM P. PRINGLE.
